UNITED STATES PATENT OFFICE.

WALLACE S. WARNOCK, OF CHICAGO, ILLINOIS.

PRINTING-PLATE HOLDER.

1,382,151.

Specification of Letters Patent. Patented June 21, 1921.

Application filed November 15, 1920. Serial No. 424,026.

To all whom it may concern:

Be it known that I, WALLACE S. WARNOCK, citizen of the United States, residing at Chicago, in the county of Cook and State of Illinois, have invented a certain new and useful Improvement in Printing-Plate Holders, of which the following is a full, clear, concise, and exact description.

My invention relates to printing plate holders and has for its general object the provision of simplified mechanism entering into the construction of the holder so that the holding jaw thereof may readily be applied to a plate to be clamped thereby and 15 may be shifted in location to suit the location of the work to be held.

In the preferred embodiment of the invention the printing plate foundation, such as the flat bed of a press or a cylindrical 20 form cylinder, is provided with cylindrical holes therein each having an annular enlargement below the work supporting face of the foundation to form a retaining shoulder. A carrier is employed that is preferably a cylindrical shell of a diameter permitting it to be passed down into any of said holes. In the preferred construction a lever is mounted upon and within the shell to be engageable beneath the retaining shoulder 25 whereby the shell and foundation are held firmly in assembly. There is a clamping jaw that desirably has an inward extension which is pivoted to and within the shell and the means for actuating the jaw is desirably 30 inclusive of a threaded rod supported at the outer end of the shell where the engaging portion of the jaw is located, and a nut threaded upon this rod, the nut having an annular groove in which a portion of the jaw 35 structure is received whereby the jaw is moved back and forth according to the direction in which the nut is turned.

The invention will be more fully set forth by a description of the preferred embodiment thereof shown in the accompanying drawing and in which Figure 1 is a side view of a part of a printing press cylinder that supports a cylindrical bed with which my plate holding mechanism is assembled; 40 Fig. 2 is a plan view, on a large scale, of the device of my invention in place within an opening in the printing foundation; Fig. 3

is a view in elevation, with parts broken away, of the structure of my invention; Fig. 4 is a sectional view on line 4—4 of Fig. 3; 55 Fig. 5 is a sectional view illustrating the shell in a mid portion within one of the holes in the printing foundation, the jaw and the mechanism for actuating the jaw being omitted in order that the lever arrangement 60 might more clearly appear; Fig. 6 is a plan view of the shell and lever mechanism shown in Fig. 5; Fig. 7 is a plan view of a sectional block formed in accordance with the invention, a suitably assembled plurality of these 65 blocks constituting a printing foundation, a printing plate being shown assembled with this block with the devices of my invention; and Fig. 8 is an end view of the block shown in Fig. 7 with the plate removed. 70

Like parts are indicated by similar characters of reference throughout the different figures.

Whether the printing bed or foundation be in the form of a cylinder 1 as indicated 75 in Fig. 1, or is flat as when it is made up of a number of sectional blocks 2 as indicated in Fig. 7, it is formed with a plurality of cylindrical holes 3 which are preferably disposed in spiral rows in the case of the rotary foundation and in oblique rows in the case of a flat bed. Each hole is desirably provided with an annular enlargement 4 below the work supporting face of the foundation whereby there is provided in each hole, preferably near the bottom thereof, an annular retaining shoulder 5. Carriers 6 are used in sufficient number to hold the printing plate or form 7 upon its bed, these carriers supporting the work engaging mechanism. 80 The carriers are preferably cylindrical in order that they may be snugly received within the holes within which they are rotatable in order that the work engaging mechanism may be positioned to suit the 85 location of the work that is to be held upon the printing foundation. A lever 8 is mounted upon and within each shell 6, there being a pin 9 upon which the intermediate portion of the lever is journaled, this pin 100 being secured at its ends to opposite portions of the shell. The lower end of the lever is formed with a nose 10 operating through a slot 11 formed longitudinally of the shell

through the lower half thereof. The lengths of the holes 3 are preferably such that the shell, when resting upon the bottom of a hole, will so position the nose 10 of the lever 5 that when the lever is swung to move this nose outwardly the nose will become engaged beneath the retaining shoulder to hold the shell and printing foundation in firm assembly. The lever projects at its upper end 10 just slightly above the shell in order that it may be grasped by the manipulator to bring the lever nose 10 into and out of position. The shell is sufficiently shorter than the hole so that the upper end of the lever will not 15 project above the work supporting face of the foundation.

As shown most clearly in Fig. 6, the shell is formed with an inturned ear 12 that serves as a detent upon the right hand side of 20 which the upper end of the lever is disposed after the nose 10 is engaged beneath the remaining shoulder 5, the detent serving to prevent the accidental releasing movement of the lever.

25 A clamping jaw 13 is located above the shell and the printing foundation. This clamping jaw preferably has an inward extension 14 pivoted within the shell upon a pin 15 that is secured to the shell. A 30 threaded rod 16 is secured at its ends to opposite portions of the upper end of the shell. A jaw adjusting nut 17 is threaded upon the rod 16 and is preferably formed with an annular groove 18 that receives the 35 jaw structure whereby the jaw is moved back and forth according to the direction in which the nut is turned. The nut may be suitably formed to enable it to be engaged by a suitable operating tool. As illustrated, the nut 40 is provided with teeth 19 on one end thereof. An adjusting hand operated rack may have its teeth brought into engagement with the teeth 19 of the nut. By moving the hand rack in one direction the nut is turned to 45 move the jaw against the work. By reversing the movement of the hand rack the jaw is withdrawn from the work.

It will be observed that the cylindrical shells may readily be turned within the holes 50 that receive them to cause the jaws to face selected directions whereby the work may be held upon the foundation in any selected position. The assembly of the plate holders with the foundation is quickly effected and 55 firmly maintained, it being impossible for the holders to fall out of place if the mechanism for assembling them with the foundation has been properly operated.

The simplicity in the construction of my 60 device and the effectiveness thereof will be readily appreciated by those skilled in the art.

While I have herein shown and particularly described the preferred embodiment of 65 my invention I do not wish to be limited to

the precise details of construction shown as changes may readily be made without departing from the spirit of my invention, but having thus described my invention I claim as new and desire to secure by Letters Patent 70 75 80 85 90 95 100 105 110 115 120 125 130 the following:—

1. The combination with a printing foundation formed with cylindrical holes therein each having an annular enlargement below the work supporting face of the foundation to form a retaining shoulder; of a carrier in the form of a cylindrical shell of a diameter permitting it to be passed down into any of said holes; a lever mounted upon and within said shell and engageable beneath said retaining shoulder; a clamping jaw located above said shell and printing foundation and having an inward extension pivoted to and within the shell; a threaded rod mounted upon and extending across said shell; and a jaw adjusting nut upon said rod and formed with an annular groove in which the jaw structure is received whereby the jaw is moved back and forth according to the direction in which the nut is turned. 90

2. The combination with a printing foundation formed with cylindrical holes therein each having an annular enlargement below the work supporting face of the foundation to form a retaining shoulder; of a carrier in the form of a cylindrical shell of a diameter permitting it to be passed down into any of said holes; a lever mounted upon and within said shell and engageable beneath said retaining shoulder; a clamping jaw upon said shell and at its outer end; and a jaw actuating device upon said shell. 100

3. The combination with a printing foundation formed with cylindrical holes therein each having an annular enlargement below the work supporting face of the foundation to form a retaining shoulder; of a carrier in the form of a cylindrical shell of a diameter permitting it to be passed down into any of said holes; a detaining element upon the shell engageable beneath said retaining shoulder; a clamping jaw located above said shell and printing foundation and having an inward extension pivoted to and within the shell; a threaded rod mounted upon and extending across said shell; and a jaw adjusting nut upon said rod and formed with an annular groove in which the jaw structure is received whereby the jaw is moved back and forth according to the direction in which the nut is turned. 110

4. The combination with a printing foundation formed with cylindrical holes therein each having an annular enlargement below the work supporting face of the foundation to form a retaining shoulder; of a carrier in the form of a cylindrical shell of a diameter permitting it to be passed down into any of said holes; a detaining element upon the shell engageable beneath said retaining 120 125 130

shoulder; a clamping jaw upon said shell and at its outer end; and a jaw actuating device upon said shell.

5. The combination with a printing foundation formed with cylindrical holes therein; of a carrier in the form of a cylindrical shell of a diameter permitting it to be passed down into any of said holes; a clamping jaw located above said shell and printing 10 foundation and having an inward extension pivoted to and within the shell; a threaded rod mounted upon and extending across said shell; and a jaw adjusting nut upon said rod and formed with an annular groove in 15 which the jaw structure is received whereby the jaw is moved back and forth according to the direction in which the nut is turned.
6. The combination with a printing foundation formed with cylindrical holes therein; 20 of a carrier in the form of a cylindrical shell of a diameter permitting it to be passed down into any of said holes; a clamping jaw upon said shell and at its outer end; and a jaw actuating device upon said shell.
- 25 7. The combination with a printing foundation formed with holes therein each enlarged below the foundation to form a retaining shoulder; of a carrier in the form of a shell of a size permitting it to be passed

down into any of said holes; a lever upon the 30 shell and engageable beneath said retaining shoulder to hold the shell and foundation together; a clamping jaw upon said shell and at its outer end; and a jaw actuating device upon said shell. 35

8. The combination with a printing foundation formed with holes therein; of a carrier in the form of a shell of a size permitting it to be passed down into any of said holes; a lever upon the shell and engageable 40 with the foundation to hold the shell and foundation together; a clamping jaw upon said shell and at its outer end; and a jaw actuating device upon said shell.

9. The combination with a printing foundation formed with cylindrical holes therein; of a carrier in the form of a cylindrical shell of a diameter permitting it to be passed down into any of said holes; a detaining element upon the shell and engageable with the 45 foundation to hold the shell and foundation in assembly; a clamping jaw upon said shell and at its outer end; and a jaw actuating device upon said shell.

In witness whereof, I hereunto subscribe 55 my name this 11th day of November, A. D. 1920.

WALLACE S. WARNOCK.
